(57) **CLAIM**

The ornamental design for a solid drawer and drawer frame, as shown and described.

DESCRIPTION

FIG. 1 is a perspective view of a solid drawer and drawer frame of my new design shown with environment;

FIG. 2 is a perspective view of a solid drawer and drawer frame shown in FIG. 1;

FIG. 3 is an elevational view of the front of the solid drawer and drawer frame of FIG. 2;

FIG. 4 is an elevational view of a first side of the solid drawer and drawer frame of FIG. 2;

FIG. 5 is an elevational view of a second side of the solid drawer and drawer frame of FIG. 2;

FIG. 6 is a top plan view of the solid drawer and drawer frame of FIG. 2;

FIG. 7 is a bottom plan view of the solid drawer and drawer frame of FIG. 2; and,

FIG. 8 is an exploded view of the solid drawer and drawer frame of FIG. 2.

The broken lines showing is included for the purpose of illustrating environment and forms no part of the claimed design.

The break lines shown in FIGS. 1 through 8 are not part of the claimed design and represent that no particular length is claimed.

1 Claim, 8 Drawing Sheets
